UNITED STATES PATENT OFFICE.

ELIAS BEACH, OF CHICAGO, ILLINOIS.

LAMP-EXTINGUISHER.

SPECIFICATION forming part of Letters Patent No. 326,707, dated September 22, 1885.

Application filed March 16, 1885. (No model.)

To all whom it may concern:

Be it known that I, ELIAS BEACH, a citizen of the United States, residing at Chicago, in the county of Cook and State of Illinois, have 5 invented certain new and useful Improvements in Lamp-Extinguishers, of which the following is a specification, reference being had to the accompanying drawings.

My invention relates to lamp-extinguishers; 10 and it consists in the peculiar construction and arrangements of parts, which will be more fully hereinafter described, and definitely pointed out in the claims.

In my application filed September 30, 1884, 15 Serial No. 144,364, and allowed March 14, 1885, an Argand burner is illustrated having a horizontal and vertical tube, with a central vertical shaft passing through the same and with a button or spreader on the upper reduced portion of said central shaft. To this 20 form of burner I preferably apply my improved extinguisher; but it is obvious that it may be applied to any other form of burner now in use.

25 The object of my invention is to provide an extinguisher which shall be simple in its construction and consequently easy of operation, and one which shall be partially self-adjustable, and thereby be free from interference with 30 any other parts of the burner. I attain these objects by the device illustrated in the accompanying drawings, wherein like letters of reference refer to similar parts in the several views, and in which—

35 Figure 1 is a sectional elevation of one form of my improved burner with the extinguishing device applied. Fig. 2 is a detail perspective view of a portion of the central vertical shaft carrying the button or spreader, showing the 40 manner of arranging the extinguisher in connection with these parts.

A represents an annular ring of metal, 45 which in its normal position lies directly under and in contact with the button or spreader W. To the under side of the ring A two bracket-arms, *a a*, are secured by any suitable means, and are so connected to the ring that they will not interfere with the extinguishing-surface thereof. These arms *a* extend downward on 50 an incline until they engage and are secured to a collar or sleeve, B, which is mounted and

has free movement on the central vertical shaft J. To the lower portion of the sleeve B one end of a flexible arm, C, is secured, which in this instance is constructed of a thin flat piece 55 of metal and twisted at a point, *c*, the lower end of said arm engaging with one of the arms of a small bell-crank lever, D, by means of eye *d* and a pivot or loop, *d'*. To the upper part of the horizontal tube H a bracket, E, is 60 secured, which is pivoted to the fulcrum-eye *d'* of the bell-crank lever D. To the third eye, *d''*, of this bell-crank lever a small wire draw-rod, F, is secured by a loop or hook, *f*, formed on the inside end thereof. This rod F 65 extends out to the exterior of the burner, and has formed on its outermost end an eye, *f'*, which has a ring or knob, F', inserted therein. Encircling this rod F is a coiled spring, G, secured at its extreme inside end to one of the 70 arms of the bell-crank lever D by suitable means, the other end of said spring being held against the inside portion of the outermost wall of the burner.

The operation of my improved extinguisher 75 is as follows: By means of the ring F', connected to the rod F, said rod is pulled out, and through the action of the bell-crank lever D and the flexible arm C, connected to said lever at one end and to the sleeve B at the 80 other, which sleeve is attached to the arms *a*, holding the annular ring A, the clear surface of the under side of the extinguishing-ring is drawn down upon the flame, thus extinguishing it. When the bell-crank lever D is drawn 85 out of its normal position, it is forced against the coiled spring E, in consequence of the spring resting against one arm of said lever, and necessarily becomes contracted so long as the rod F is drawn out; but when said rod 90 F is released the resilient force of said coiled spring forces the arm of the bell-crank lever, against which it rests, back to its normal position, and consequently the annular extinguishing-ring resumes its normal position under the button or spreader W.

95 By having the extinguishing surface constructed in the form of an annular ring the tendency toward an explosion is avoided when the said ring is suddenly brought in contact 100 with the flame, for if any gases have arisen in any of the tubes with which it comes into con-

tact during the process of combustion they are allowed to escape through the opening of said extinguisher, as well as at the outer edge thereof, and ascend up through the globe or chimney. This extinguishing-ring is constructed of such diameter or width that when it is lowered it covers the wick and the outside edge of the wick-tube, thus covering the entire source of flame.

10 By the simple construction and arrangement of my device, and its efficiency of operation, an extinguisher is provided which can be cheaply manufactured, readily applied, and at the same time be safe and economical in its use.

15 Having thus described my invention, what I claim as new, and desire to secure by Letters Patent, is—

1. The combination, with an Argand burner, of a central shaft supporting a spreader, an annular extinguishing-ring resting against said spreader with suitable supports for holding said ring on said shaft, and means for raising and lowering said ring, substantially as described.

25 2. The combination, with an Argand burner, of a central shaft supporting a spreader, an annular ring resting normally against said

spreader, a sleeve encircling said shaft and attached to said ring by bracket-arms, and means for operating said sleeve to raise and lower the extinguishing-ring, substantially as described, and for the purposes set forth.

3. The combination, with an Argand burner, of a central shaft, a spreader, an extinguishing-ring resting normally against said spreader and movably secured to said shaft by means of a sleeve and bracket-arms, a flexible arm attached to said sleeve, a bell-crank lever hinged to said arm and to said burner, a draw-rod, a spiral spring mounted thereon, and a ring for operating said draw-rod, substantially as described.

4. The combination, with an Argand burner, of a central shaft, an annular ring, A, bracket-arms a a, sleeve B, flexible arm C, bell-crank lever D, hanger E, draw-rod F, spiral spring G, and a ring, F', arranged as described, and for the purposes set forth.

In testimony whereof I affix my signature in presence of two witnesses.

ELIAS BEACH.
